UNITED STATES PATENT OFFICE.

DONALD M. SIMONS, OF OSBORNE, PENNSYLVANIA, ASSIGNOR, BY MESNE ASSIGNMENTS, TO GENERAL CABLE CORPORATION, A CORPORATION OF NEW JERSEY.

CABLE STRUCTURE.

Application filed March 19, 1925, Serial No. 16,732. Renewed September 15, 1928.

My invention relates to improvements in the structure of and in the method of operation of high-tension electric cables. The invention is illustrated in the accompanying drawings, in which Fig. I is a view in transverse section of a three-conductor cable in the use of which my invention may be employed. Fig. II similarly shows a cable in which an alternative form of structure is employed for the practice of my invention. Fig. III diagrammatically illustrates a detail of installation.

There is known to the art a certain high-tension electrical cable, characterized by having a thin and closely adherent and grounded envelope of metal, surrounding the insulated conductor within the cable sheath. Cables of this general character are in practical use, particularly multiple-conductor cables, in which each separately insulated conductor is separately surrounded by a thin, grounded envelope of metal. The effect of the envelope is to limit voltage stresses to the body of insulation enveloped, and to relieve bodies of insulation external to the envelope of such stresses.

When such a cable is put to use spaces are likely to develop within the cable sheath and externally of the individually insulated conductors. Such spaces may develop in consequence of the bending of the cable during installation, or they may appear in consequence of temperature changes. It is primarily to prevent sparking and glowing in such spaces (however developed) that the invention of a metallic envelope upon the individually insulated conductor alluded to above is intended.

Whatever the particular cause of their development may be, I have discovered that such spaces when they occur still continue to be a source of difficulty, even though the invention just alluded to be employed; I have discovered that, when such spaces appear, insulating compound, particularly if it be very fluid, is liable to migrate from the body of insulation which surrounds the individual conductor and which the envelope of thin metal immediately overlies, in order to fill these spaces. The thin metal envelope is ineffective to prevent this, for in the usual embodiment of the invention alluded to the envelope intentionally is made pervious to insulating compound, that the underlying body of insulation may, after

building, be impregnated. The effect of such migration is that new vacancies are opened within the body of insulation which immediately surrounds the individual conductor, and upon which the thin metal envelope is immediately applied, and such vacancies tend to break-down.

My invention consists in establishing within the sheath of a cable having the particular character described, a flood of insulating compound under sufficient head, always ready to flow and to occupy spaces within the cable sheath as they open, thus preventing migration of compound from the body of insulation which immediately surrounds the individual conductor, and preventing the said tendency to break-down.

In a multiple-conductor cable the spaces between the individually insulated conductors and the all-including cable sheath (and beneath the belt insulation, if a belt be employed) are ordinarily filled with bodies of relatively inferior insulation, ordinarily jute. These bodies are termed fillers, and in the three-conductor cable, which is the commonest form of multiple-conductor cable, there are four fillers,—three laterals and one central.

These filler bodies are ordinarily themselves pervious to a flood of insulating compound, and it is possible to cause the flood of insulating compound which the practice of my invention requires, to penetrate the fillers of the otherwise normal construction. Preferably, however, I make provision for the more rapid and more effective flow of and distribution of the flood of compound by removing one or more of the fillers of the normal assembly and by employing the space so afforded as the conduit for the flood of insulating compound. I may make no other provision, but may allow the walls of the adjacent cable parts to constitute the limiting walls of such conduit. Preferably, however, I introduce into such space a conduit as a separate structure; and where, in the ensuing claims, I employ the word "conduit" I define thereby a conduit as a separate structure. This specially prepared conduit may or may not fill the whole space; and, if it does not, jute or other suitable material may be employed to fill the otherwise unoccupied space. The conduit may be circular in cross-section or it may be particularly shaped, for example

to the approximately sector shape of the lateral space in a three-conductor cable. It may be formed of flexible, and even somewhat elastic material, and so when applied 5 and filled with liquid under pressure, it may shape itself to and enlarge to fullest extent and fully occupy the space in which it is set.

Referring to Fig. I of the drawings, a three-conductor cable is shown. The conductor is indicated at 1; 2 is the body of insulation applied immediately to the conductor. Ordinarily it takes the form of wrapped-on paper tape, impregnated with insulating compound. 3 is the metal envelope, pervious 15 to the passage of compound, which immediately surrounds the individually insulated conductor. 4 is the cable sheath, ordinarily of lead. Within the sheath and externally of the individually insulated and metal-enveloped conductors the spaces are filled with bodies 7, commonly called fillers, and these bodies ordinarily are formed of such relatively inferior material as jute. The fillers may be composed of material so porous and so 25 penetrable by a flood of insulating compound that my invention may be practiced upon the cable without structural change. The spaces in which the fillers are contained may constitute a conduit, in which, in spite of the presence 30 of the filler bodies themselves, the flood of insulating material under pressure, in which my invention centers, may be maintained.

Alternately, as illustrated in Fig. II, one or more of the fillers may be omitted, and in its place a conduit 8 may be introduced, having the characteristics to be specified below, and through this conduit the flood of insulating compound may be maintained, available 40 to correct injury and to prevent damage at any point throughout the length of the cable.

Since in the cable with which I have to do the voltage stresses are limited by the metallic envelope which immediately overlies 45 the body of insulation surrounding the individual conductor, the conduit which I may employ in the practice of my invention, may be of conducting or of non-conducting material; it may be of metal, for instance; it 50 may be simply a metal pipe arranged in one of the lateral spaces or in the central space. In any case, it should be pervious, and if therefore it be formed of metal, the metal wall will be perforated and the perforations will 55 be of sufficient size and frequency to render the flood of liquid responsive to the danger conditions already indicated. Instead of a metal pipe with perforated walls, a conduit formed of porous material may be employed, 60 through whose pores the flood of liquid will flow to achieve the end in view. Textile material, for example, may be employed, of fine woven wire or of thread formed of plant fibre; or paper or cardboard may be employed. 65

At suitable points throughout the extent of an installation, as for example at joints and at terminals, as above explained, reservoirs may be provided, and provisions adopted for maintaining within the cable structure 70 the desired flood of liquid under desired pressure. Fig. III shows a reservoir 9 arranged at a cable joint. The joint casing is indicated at 10, and with the space within, the reservoir has connection. Within the reservoir a supply 75 of compound may be maintained, and pressure, due to head, or due to special pressure-imparting means, may be transmitted from the body of compound within the reservoir to the flood of insulating compound within the cable, throughout all the extent of the cable. 80

Whatever specific provision be made for the presence of a flood insulating compound, such body of insulating compound present within the cable sheath may at all times while the cable continues in service, and if desired while installation is being effected, be maintained under pressure. When conditions transpire which otherwise would 90 result in the opening of a space, the flood of insulating compound migrating under pressure will occupy and prevent the opening of such space. If a space has opened, the flood of compound under pressure will occupy and 95 close the space, and prevent migration of compounds from the insulation which surrounds the conductors individually. My invention, then, makes for greater and better efficiency of a cable of the type described 100 above and characterized by an envelope of metal foil or equivalent material applied immediately upon the insulation surrounding the individual conductor. 105

It will be remarked of the structure of my invention that the conductor 1 with the body of insulation 2 enveloped in the pervious layer 3 constitutes a unit which is accessible to a flood of liquid under pressure over its exterior surface only, and that from the exterior surface only of this unit can there be 110 escape of liquid. Elsewhere, the unit is closed to liquid flow.

I have used in this specification the term insulating compound, and the term has specific meaning in the art, and signifies an oil or a mixture of oils and other substances, such as are commonly used in such cases. The invention is applicable, as will be perceived, whatever be the particular liquid employed. 115

I claim as my invention:

1. In a multiple-conductor cable the combination of a plurality of individually insulated metal enveloped conductors cabled within a sheath with filler spaces between, the metal envelope of each insulated conductor being penetrable by liquid insulating material, and the insulation immediately surrounding each conductor and within the metal envelope consisting of permeable ma- 120

terial filled with liquid insulating material, and a flood of liquid under pressure maintained within the filler spaces.

2. In a multiple conductor cable the combination of a plurality of individually insulated conductors, a metal envelope surrounding each insulated conductor, the said envelopes being penetrable by liquid material, an imperforate sheath surrounding the indi-

vidually insulated metal sheathed conductors 10 so as to form filler space therebetween, a conduit in the filler space, the wall of said conduit being penetrable by liquid material, and liquid insulating material under pressure filling the conduit and the filler space. 15

In testimony whereof I have hereunto set my hand.

DONALD M. SIMONS.
